UNITED STATES PATENT OFFICE.

GEORGE H. BACKMIRE, OF COLLEGEVILLE, PENNSYLVANIA.

HOLDER OR SUPPORT.

Application filed October 8, 1920. Serial No. 415,488.

To all whom it may concern:

Be it known that I, GEORGE H. BACKMIRE, a citizen of the United States, residing at Collegeville, in the county of Montgomery and State of Pennsylvania, have invented new and useful Improvements in Holders or Supports, of which the following is a specification.

My invention relates to new and useful improvements in holders or supports, and has for its object to provide an exceedingly simple and effective device of this character which may be formed from a single piece of wire so coiled and bent or fashioned as to provide a stake clamp and holding ring, a loop and hook engaging said loop to hold the ring in a closed position.

Another object of the invention is to provide a support, the ring of which is provided with a number of stake loops in addition to the other elements above mentioned.

A further object of the invention is to provide a stake clamp for supports of the character herein referred to comprising two spaced coils arranged at diverging angles to each other and joined together by a wire strand having sufficient resiliency to act as a spring to cause the coils to bind upon the stake on which they are mounted thereby producing sufficient friction to hold the clamp in its adjusted position.

With these ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawings forming a part of this application, in which:—

Fig. 1, is a side elevation of my improved holder or support showing it applied to a section of a stake.

Fig. 2, is an end view thereof the ring being broken away.

Fig. 3, is a plan view of Fig. 1.

Fig. 4, is a plan view of the holder showing a slightly modified form of construction with the ring open.

Fig. 5, is a perspective view of that form wherein the ring is provided with a plurality of stake loops showing said support

in use with a number of stakes for enclosing a plant or plants.

Fig. 6, is a side elevation of the device with the ring eliminated.

In carrying out my invention as embodied in Figs. 1 to 3 inclusive, 2 represents the holder or support comprising a ring 3 which may be of any desirable size and in the strand or wire forming this ring is produced a fastening loop 4 adapted to be engaged by a hook 5 formed from the free end of the ring and when said hook is in engagement with said fastening loop the ring will be maintained in its closed position as shown in Fig. 3. To the rear of the fastening loop is formed the upper coil 6 of the stake clamp and which is of sufficient diameter to freely slip over a stake 7 with which the holder or support is to be used; from the upper coil 6 projects the strand or connecting member 8 from which is formed the lower coil 9 of the stake clamp and these coils 6 and 9 are arranged at angles opposite to each other as shown in Fig. 2 so that when placed upon a stake of the proper size 80 they will bind upon the same and maintain the support or holder in any desired adjusted position, yet with very little effort said holder or support may be moved up or down upon a stake or entirely removed 85 therefrom as occasion requires.

In Fig. 4, I have shown a slightly modified form of hook engaging means or complementary fastening means 4^a in the form of an indent or approximate semi-circle formed 90 from the section of wire producing the ring.

In Fig. 5, I have shown the ring of the holder or support provided with a plurality of stake loops 10 which are of sufficient diameter to freely pass over the additional stakes 11, which, with the holder supporting stake 7 from an enclosure for a plant, said loops preventing said stakes from being forced apart. These loops are spaced apart about the ring and are produced from the same section of wire which forms the ring and in all other respects the construction is identical with the form of device illustrated in Fig. 1.

From the foregoing description it will be seen that I have produced an exceedingly simple support and stake clamp combined, the elements of which are formed from a single piece of wire and which may be held in any adjusted position upon a stake with- 110

out the use of elements requiring tools to adjust them.

In Fig. 6 I have shown the stake clamp without a ring thereby forming a support for string wire and the like and when in use the string is passed through the loop 4^b which in this case is not used as the complementary fastening member but in the form of an eye for threading the string 10 therethrough.

This device is particularly adapted to use as a plant holder or trellis for maintaining the plant in an upright position and confining the same, but it will be readily understood that the invention is also applicable as a support or hanger for clothing and for articles to be exhibited.

Of course I do not wish to be limited to

the exact details of construction as herein shown as these may be varied within the 20 limits of the appended claim without departing from the spirit of my invention.

Having thus fully described my invention, what I claim as new and useful is:—

A plant support comprising two coils arranged at different angles to each other, a connecting member holding said coils in spaced relation, a plant ring projecting from one of said coils, a hook formed from the free end of said ring, a complementary fastening member with which said hook 25 30 co-acts, and a plurality of stake loops formed at different points about said ring.

In testimony whereof, I have hereunto affixed my signature.

GEORGE H. BACKMIRE.
